UNITED STATES PATENT OFFICE.

HARRIS W. SLATER, OF LAKE MAHOPAC, NEW YORK, ASSIGNOR TO THE NATIONAL MACHINE COMPANY, OF MAMARONECK, NEW YORK, A CORPORATION OF NEW YORK.

THREAD-TRIMMING DEVICE FOR SEWING-MACHINES.

No. 908,618.

Specification of Letters Patent.

Patented Jan. 5, 1909.

Application filed January 25, 1907. Serial No. 353,939.

To all whom it may concern:

Be it known that I, HARRIS W. SLATER, a citizen of the United States of America, and a resident of Lake Mahopac, county of Putnam, State of New York, have invented certain new and useful Improvements in Thread-Trimming Devices for Sewing-Machines, of which the following is a specification, reference being had to the accompanying drawings, forming a part thereof.

My invention relates to thread trimming devices for sewing machines, and particularly to thread trimming devices adapted for trimming the needle thread of a button-hole sewing machine, or other machine for producing groups of stitches at predetermined points.

My invention consists in means for nipping the end of the needle thread to hold same after the group of stitches has been completed and before the removal of the work, the act of removing the work operating to sever the thread thus held, and also to sever the thread end which may protrude from the work at the point of commencement of the group of stitches. By this means the two threads are severed close to the work, while the end of the needle thread is securely held, so that the same will not be withdrawn through the eye of the needle when the new stitching operation is commenced.

In order that my invention may be fully understood, I will describe in detail an embodiment thereof, having reference to the accompanying drawings illustrating same, and will then point out the novel features in claims.

In the drawings: Figure 1 is an end view of a buttonhole sewing machine, with my improved thread trimming and nipping device employed in connection therewith. Fig. 2 is a top view in detail of certain parts of the machine including the work clamp and the thread trimming device which is mounted thereon. Fig. 3 is a detail sectional view through the work clamp, the plane of section being taken substantially upon the line 3—3 of Fig. 2. Fig. 4 is an end view of the work clamp and of the thread trimming mechanism. Fig. 5 is a detail view in horizontal section of certain parts of the thread trimming and gripping mechanism. Figs. 6, 7 and 8 are detail sectional views substantially upon the line 6—6 of Fig. 2,

showing the thread trimming and gripping device in different positions with relation to the part of the work clamp which supports the same.

The sewing machine illustrated is of the buttonhole variety, comprising the usual bed plate 10 and overhanging arm 11, a laterally vibrating and vertically reciprocating needle bar 12 being mounted in the end head of the said overhanging arm 11, all as will be well understood by those skilled in the art to which this invention appertains. The work is presented for stitching by a work clamp comprising a relatively stationary bottom plate 13, and a relatively movable upper member 14 pivoted to the lower plate at 15, and carrying a presser foot 16 arranged to bear upon the work and press same down against the lower plate 13, a spring 17 being employed to apply the proper yielding pressure to the said upper member for this purpose. Suitable feeding movements are imparted to the work clamp as a whole through the medium of a feed plate 18, one end of which appears in Fig. 2, said feed plate carrying said work clamp bodily, and itself operated by the usual or any desired mechanism. (Not shown.)

The mechanism constituting the invention herein comprises a star wheel 19 mounted beneath a plate 20 formed as a part of the upper work clamp member 14. The said star wheel is secured to a vertical stud 21, which is mounted to rotate in the said plate 20, a pinion 22 being also secured to the said stud and arranged above the said plate 20. The extending arms of the star wheel, of which there are four in the present instance, are arranged to travel between the under side of the plate 20 and the upper face of a thread guiding member 23. Said thread guiding member has an offset portion 24 which is secured against the under side of the plate 20 beyond the arms of the said star wheel by means of a stud or bolt 25. The arms of the star wheel 19 thus pass between two surfaces, one the under surface of the plate 20, as aforesaid, and the other the upper surface of the thread guide 23. The said surfaces co-act with the upper and lower surfaces of the arms of the star wheel to form thread gripping means, either of the pairs of co-acting surfaces forming an effective device for nipping a thread between them.

23

The star wheel may be given a step by step movement of rotation by any suitable means, the means herein shown comprising a ratchet wheel 26, a pawl 27 therefor, said pawl mounted upon an operating arm 28, and a spur gear 29 in mesh with the pinion 22 and secured to rotate with the ratchet wheel 26. The ratchet wheel 26 and the spur gear 29 are both mounted upon a stud 30, itself mounted to rotate in the plate 20, while the operating arm 28 is mounted loosely upon the said stud, so that it may have a free rotative movement with respect thereto. Pivoted to the outer end of the operating lever 28 is a follower bar 31, said follower bar arranged to have a sliding engagement with a bearing member 32, the free end of said bar being in the path of a tappet or cam 33 carried by a rock shaft 34. A retractile spring 35, between the bar 31 and a relatively stationary portion of the machine, tends to draw the bar 31 up to the cam and maintain the end of the said bar in contact with the working face of the aid cam. A rocking movement imparted to the rock shaft 34 will reciprocate the bar 31, the operating arm 28 being oscillated thereby, and a step by step movement thus imparted to the star wheel. The rock shaft 34 is arranged to be operated by an attendant, an operating arm 36 being provided for this purpose. The ordinary function of the said rock shaft 34 is to lift the upper member 14 of the work clamp after the completion of a buttonhole, a cam or tappet 37 thereon being arranged to engage an extension 38 of the said clamp member 14, the said extension being on the opposite side of the pivotal support 15, so that, by depressing the said extension 38, the member 14 as a whole is lifted. The relation of the two cams or tappets 33 and 37 is such that the said cam or tappet 33 will commence to operate immediately the rock shaft 34 is moved, while the cam or tappet 37 will not come into play until the latter part of the movement of the rock shaft, so that the movement imparted to the operating arm 28 through the follower bar 31 will surely be completed when the member 14 is lifted. It will be remembered that the member 14 is lifted to permit the removal of the work after the completion of the stitching for a buttonhole or other group of stitches, and it is at this time that it is required to nip the needle thread so as to permit severance thereof near the work, and to hold the thread end for a new stitching operation. The operation, then, of the rock shaft 34 by the attendant upon the completion of the buttonhole, will operate to give a step by step movement to the star wheel a distance between two of its arms (in this case one quarter of a revolution.) The arm of the star wheel coming into play at this time,

moves across the path of the needle thread, hence such arm will carry a loop of the needle thread with it to its new position between the plate 20 and the thread guide 23 (see Fig. 6 of the drawings.) The thread 70 will be nipped by the gripper in two places between the lower surface of the plate and the upper surface of the star wheel arm, and between the lower surface of the star wheel arm and the upper surface of the 75 thread guide 23. It will be noticed that the thread guide 23 is forked at the end at which it receives the thread, so as to properly guide the thread to a central position with respect thereto. During the latter 80 part of the movement of the rock shaft the upper member 14 will be lifted bodily to release the work, so that the work may be drawn out by the attendant and re-positioned for a new sewing operation. The 85 act of drawing out the work, however, will sever the thread. This severance is accomplished by means of a stationary knife blade 39 located beneath the thread guide 23 with its cutting edge across the bifurcated end thereof. The thread in being nipped will be presented against the face of this cutting knife, so that the movement of the work will readily effect the severance of the thread, as will be well understood. A 90 thin plate 40 is supported beneath the said knife blade 39 having a bifurcated end in register with the bifurcated end of the thread guide 23 to form a supplemental thread guide and to insure the proper presentation of the thread to the trimming knife for a cutting operation.

In Fig. 6 the parts are shown with the work in a position just ready for a cutting operation, the thread end which goes to the 105 needle being securely held by the thread nipping or gripping device. In Fig. 7 the parts are shown in their positions following the commencement of a new sewing operation. The new end will now be seen to have been 110 received by the work and to extend between the work and the gripping device. The entire operation of sewing a buttonhole may now take place with the thread end still held in this position, as it is not necessary 115 to relieve the same, on account of the thread nipping device being carried by the work clamp, and hence being moved with the work. When the new group of stitches has been completed and the star wheel has again 120 been moved to carry over a new loop of the needle thread and nip the thread end, the thread end left at the beginning of the sewing operation may be momentarily released by such movement of the star wheel, the free 125 end being, however, carried over and allowed to lie on top of the thread guide 23. The arm of the star wheel, which comes into play to replace the arm which has gone forward, will re-nip this free thread end be- 130

tween its lowest surface and the upper surface of the thread guide 23, so that now the two thread ends will be held by the gripping device, one the thread projecting from the work at the beginning of the sewing operation, and the other the thread projecting from the work at the completion of the sewing operation, the latter thread going up the needle. Removal of the work will sever both threads quite close to the work, and, as set forth above, will hold the needle thread for a new operation. Fig. 8 shows the star wheel as just moving into position to grip both thread ends, the thread end from the commencement of the work lying free upon the upper surface of the thread guide 23.

What I claim is:

1. In a sewing machine, the combination with a work clamp and stitch forming mechanism employing a needle thread, of an arm having upper and lower gripping surfaces, the said arm arranged to move laterally across the path of the needle thread and to engage and carry a loop of such thread with it, upper and lower thread gripping surfaces arranged stationary upon the work clamp with which the upper and lower surfaces of the said arm are adapted to co-act, both of said upper and lower pairs of co-acting surfaces adapted to grip and hold a thread between them, and a cutter arranged to cut the thread at a point between the work, and the point at which the thread is gripped.

2. In a sewing machine, the combination with a work clamp and stitch forming mechanism employing a needle thread, of an arm arranged to move laterally across the path of the needle thread and to engage and carry a loop of such thread with it, a stationary gripping surface arranged beneath the said arm for co-acting therewith, and a thread trimming knife arranged beneath the said co-acting surfaces adapted to trim the thread held by the gripper, such trimming being effected by the act of removing the work from a sewing position, the said thread trimming knife being mounted stationary upon and carried by the said work clamp.

3. In a sewing machine, the combination with stitch forming mechanism employing a needle thread, of an arm arranged to move laterally across the path of the needle thread and to engage and carry a loop of such thread with it, upper and lower thread gripping surfaces with which the upper and lower surfaces of the said arm are adapted to co-act, both of said upper and lower pairs of co-acting surfaces adapted to grip and hold a thread between them, and a stationary thread trimming knife arranged beneath said surfaces adapted to trim the thread held by the gripper, such trimming being effected by the act of removing the work from a sewing position.

4. In a sewing machine, the combination

with stitch forming mechanism employing a needle thread and arranged to produce a group of stitches, of two sets of thread gripping means for simultaneously gripping the free end of the thread extending from the work at the point of commencement of the sewing, and the thread extending from the work at the point of completion of the sewing, the latter said thread being the thread which passes to the needle of the machine, and a stationary thread trimming knife, arranged between the gripping means and work position, whereby the act of removing the work from its sewing position will cause the said knife to sever both the said threads.

5. In a sewing machine, the combination with stitch forming mechanism employing a needle thread, and a work clamp for presenting work for a stitching operation, said work clamp including an upper member carrying a supporting plate, of an arm pivoted immediately beneath said plate arranged to swing in a horizontal plane across the path of the needle thread, a thread guide mounted immediately beneath the said arm, the said arm adapted to co-act for a gripping operation with the under surface of the said plate and with the upper surface of the said thread guide, a stationary thread trimming knife carried by said work clamp immediately beneath the thread guide, means for operating said work clamp to release the work therefrom, and mechanism also operated by said means for operating the said swinging arm.

6. In a sewing machine, the combination with stitch forming mechanism employing a needle thread, of a star wheel having arms arranged to move across the path of the needle thread, upper and lower thread gripping surfaces with which the arms of the said star wheel are adapted to engage, the said upper and lower surfaces and the upper and lower surfaces of the arms of the said star wheel constituting two sets of gripping surfaces in different planes each of which is adapted to engage and hold a thread, means for imparting step by step movements to the said star wheel, and a stationary thread trimming knife arranged contiguous to the thread gripping surfaces and beneath the same, substantially as set forth.

7. In a sewing machine, the combination with stitch forming mechanism employing a needle thread, of a work clamp for presenting work for stitching, a star wheel carried by said work clamp, the arms of said star wheel arranged to co-act with a relatively stationary portion of said work clamp to form a pair of gripping surfaces, a thread guide mounted beneath the path of movement of said star wheel, said thread guide and star wheel arms forming a second pair of gripping surfaces, a stationary trimming knife mounted beneath said thread guide,

and means for imparting step by step movements to the said star wheel.

8. In a sewing machine, the combination with stitch forming mechanism employing a needle thread, of a work clamp for presenting work for stitching, a star wheel carried by said work clamp, the arms of said star wheel arranged to co-act with a relatively stationary portion of said work clamp to form a pair of gripping surfaces, a thread guide mounted beneath the path of movement of said star wheel, said thread

guide and star wheel arms forming a second pair of gripping surfaces, a stationary trimming knife mounted beneath said thread guide, means for operating said work clamp to release the work held thereby, and mechanism operated by the same means which so operates the work clamp for imparting step by step movements to the star wheel.

HARRIS W. SLATER.
